CLAIM

We claim the ornamental design for a vacuum cleaner, as shown and described.

DESCRIPTION

FIG. 1 is a front perspective view of a vacuum cleaner showing our new design;
FIG. 2 is a rear perspective view thereof;
FIG. 3 is a front view thereof;
FIG. 4 is a rear view thereof;
FIG. 5 is a left side view thereof;
FIG. 6 is a right side view thereof; and,
FIG. 7 is a top view thereof.
Elements shown in broken lines form no part of the claimed design.
